United States Patent

Des. 241,514
Patented Sept. 21, 1976

241,514

DECORATOR CLIP

Orville T. Stall, Newport Beach, Calif.
(13545 Excelsior, Norwalk, Calif. 90650)

Filed Nov. 10, 1975, Ser. No. 630,691

Term of patent 14 years

Int. Cl. D8—08

U.S. Cl. D8—248

FIG. 1 is a perspective view of a decorator clip, the broken lines being for illustrative purposes only.

FIG. 2 is an end view of the design;

FIG. 3 is a front view of the design;

FIG. 4 is a back view of the design;

FIG. 5 is a top view of the design; and

FIG. 6 is a bottom view of the design.

I claim:

The ornamental design for a decorator clip, as shown and described.
